UNITED STATES PATENT OFFICE

HENRY F. SCHMIDT, OF LANSDOWNE, PENNSYLVANIA, ASSIGNOR TO WESTINGHOUSE ELECTRIC & MANUFACTURING COMPANY, A CORPORATION OF PENNSYLVANIA

CONDENSER FOR STEAMSHIPS

Application filed May 18, 1926. Serial No. 109,949.

My invention relates to marine power systems, particularly to power systems embodying steam turbines and condensers and it has for an object to provide apparatus of the 5 character designated which shall be extremely compact in design and efficient in operation.

These and other objects, which will be made apparent throughout the further description of my invention, may be obtained by the 10 employment of the apparatus hereinafter described and illustrated in the accompanying drawings in which:

Fig. 1 is a plan view of one form of power system arranged in accordance with my invention;

Fig. 2 is a partial transverse, sectional view taken on the line II—II of Fig. 1;

Fig. 3 is a longitudinal elevation showing the inboard portion of the power system illustrated in Fig. 1; and,

Fig. 4 is a longitudinal sectional view taken on the line IV—IV of Fig. 2.

It is generally appreciated in power plant practice that it is highly desirable, from a 25 drainage standpoint, to place the turbine at a higher elevation than the condenser to which it exhausts and, in most stationary power plants, the turbine is mounted directly over the condenser for this reason. It is also desirable that the condensate be removed 30 at as high a temperature as possible and that the air and non-condensable gases be removed at as low a temperature as possible in order that, in the first instance, all possible heat 35 may be conserved and, in the second instance, that the amount of energy required for removing the air and non-condensable gases be reduced to a minimum.

While it has been possible heretofore to 40 arrange a power system for stationary plants that would embody all of the aforementioned conditions, nevertheless this has not been generally possible in marine installations. This has been due principally to the fact that condensers, as heretofore constructed, were necessarily of such depth that mounting a turbine upon them caused the turbine to be located at such a relatively high elevation as to necessitate an undesirable downward inclination 45 of the ship's propeller and line shafting.

It has, as a consequence, been the general practice to locate the condenser by the side of the turbine in order that the turbine may be disposed at a sufficiently low elevation to permit the shafting connecting the propeller and the turbine to be disposed in substantially a horizontal plane. Such an arrangement, however, occupies considerable space and necessitates the use of very large and cumbersome exhaust trunks for connecting 55 the turbine to the condenser.

All of the foregoing difficulties are overcome by my invention in which the condenser is made relatively wide and shallow and located extremely low in the ship. This is accomplished by supporting the condenser directly upon the ship's structure and having its lower portion conforming in contour substantially with that of the ship's lines. The condenser is so arranged that the upper shell 60 portion extends horizontally inboard from the side of the ship, forming with the lower shell portion a tube nest deepening as it approaches inboard. The turbine elements are then mounted directly on this upper horizontal shell portion of the condenser so that the condenser itself serves as a foundation for the turbine elements. In cases where cross-compound turbines are employed and in 65 which some of the elements do not exhaust 70 to the condenser, I may arrange my condenser so that it supports not only the elements exhausting to it but the other turbine elements as well. In this way, the entire 75 turbine, no matter how many elements it may comprise, may be supported directly upon the condenser. As the latter is made so as to conform to the ship's structure, it may be located unusually low in the ship and the turbines are consequently disposed at such a relatively 80 low elevation as to permit the shafting connecting the propeller and the turbines to be disposed in substantially a horizontal plane. In this way, very effective turbine 85 drainage is assured.

I prefer to so arrange the various turbine elements on the top of the condenser that the low pressure element or the elements exhausting thereto are located inboard above the deepest portion of the condenser. By means 90

of such an arrangement, the air offtake may be located at the outboard or shallow portion of the condenser where it is disposed at a maximum distance from the exhaust inlet. 5 On the other hand, I prefer to locate the condensate outlet in the inboard or deeper portion of the condenser close to the exhaust inlet in order that the temperature of the condensate may approach the temperature of the exhaust steam as closely as possible. In 10 view of the fact that my entire condenser must be made relatively shallow, I arrange the tube nest in a novel manner in order to provide a large distributing space as well as a large entrance area for the exhaust steam. 15

Referring now to the drawings for a more complete description of my invention, I show in Fig. 1 a power installation comprising a ship's structure 10 within which is disposed a cross-compound turbine embodying a high-pressure element 11 and a low-pressure element 12, said high-pressure element 11 exhausting into the low-pressure element 12 through a conduit 13. The turbine elements 11 and 12 are arranged to drive a single propeller shaft 14 through a suitable reduction gear 15 and they are mounted or supported upon a condenser 16. Circulating water is delivered to the condenser 16 by what is known as the scoop method, the water entering through an inlet 18 which may project through the ship's structure and connect with a suitable water box 19 of the condenser. Water leaves the condenser through a water box 22 which connects with an overboard discharge pipe 23, the pipe 23 being arranged to pass under the casing of the reduction gear 15. While I have shown my condenser as being of a type adapted to be supplied with water by the scoop system, nevertheless, it is apparent that the condenser may be readily supplied with water by circulating pumps in the usual manner. 35

Referring now particularly to Fig. 2, the condenser is somewhat of a right-triangular shape in cross-section with the longer side of its shell portion, shown at 26, conforming substantially with the contour of the ship's structure. The upper side of the shell portion, shown at 27, extends horizontally and is connected to the ship's structure and to the shell portion 26. In the present arrangement, the upper horizontal shell portion 27 serves as a foundation or base plate for all 50 of the turbine elements. The condenser shell is completed by a vertically disposed shell portion 28 which defines the deeper portion of the tube nest. As shown in Fig. 3, the shell portion 28 serves as a supporting structure for the inboard and of the condenser, it being firmly secured to the structure of the ship and provided with suitable stiffening members 29. The lower shell portion 26 is connected to the vertical shell portion as 55 shown at 30.

The low-pressure turbine element 12 is supported upon the inboard or deeper portion of the condenser, the exhaust steam being admitted to the condenser through the inlet 31, shown in Fig. 2. The high-pressure turbine element is supported upon the outboard or shallow portion of the condenser. In order to provide the required supporting strength for both of these turbine elements, I prefer to provide within the condenser a longitudinally extending girder 32 which is disposed between the upper horizontal shell portion 27 and the lower shell portion 26. Disposed beneath the girder 32 are suitable bearing pads 33 which rest upon proper seatings 34 secured to the ship's structure. The girder 32 is provided, as shown particularly in Fig. 4, with suitable openings 35 for permitting communication between the inboard and outboard portions of the condenser. 75

While I have shown one form of girder for stiffening the condenser and for supporting the various turbine elements, nevertheless it will be understood that it is within the purview of my invention to provide any number or type of internal supporting members as may be required by the type or size of turbines which it is proposed to support upon the condenser. 90

Disposed in the outboard portion of the condenser, at a remote distance from the exhaust inlet 31, is an air and non-condensable gas outlet 36. Suitable baffles 41 are interposed between the exhaust inlet 31 and the air outlet 36 in order to produce a tortuous 100 passage for the gases in order that they may be cooled to as low a temperature as possible before passing through the outlet 36.

The condensate outlet is located at 37 in the inboard or deeper portion of the condenser and is so arranged that it is in contact with the entering steam in order that the temperature of the condensate may be maintained at as high a temperature as possible. A suitable condensate removal conduit 38 is 110 provided which is arranged in the well-known manner so as to maintain a liquid seal in order that gases which have not been condensed may not escape from the condenser. 105

Arranged within the condenser 16 is a tube nest 39 which completely fills the outboard or shallow portion of the condenser but which is so arranged as to have its inboard portion only partly filled, the contour of the tube nest being preferably arranged as illustrated 120 and having an inboard margin such as indicated at 40.

From the foregoing description, the operation of my apparatus will be readily apparent. Steam exhausted from the low-pressure 125 turbine element 12 enters the condenser through the exhaust inlet 31 wherein the inclined arrangement of tubes gives a large distributing space and large entrance area between the tubes. The steam is drawn past 130

the tubes toward the air outlet 36, the steam in its passage going through the openings provided in the supporting girder 32. In its passage past the cooling tubes, the steam is condensed and drains downwardly to the lower portion of the condenser to the condensate outlet 37. As the condensate outlet 37 is so arranged as to be in the vicinity of the inlet 31, the condensate assumes a temperature which closely approaches that of the entering steam, a very desirable feature. The air and non-condensable gases are drawn to the outboard end of the condenser and pass through the outlet 36, their path of travel being extended by the baffles 41.

It is, therefore, evident that by means of such an arrangement, the condensate leaving the condenser is at a maximum temperature while the air and non-condensable gases are at a very low temperature. Furthermore, as all of the turbine elements, not only the low-pressure element, but the high-pressure element as well, are located above the condenser, perfect drainage of the entire turbine is assured at all times. Furthermore, as the condenser is made to conform to the contour of the ship's structure, it occupies a minimum amount of space and it may be made so shallow that the turbines may be disposed at approximately the same horizontal elevation as the propeller. In addition, the condenser structure serves both as a shell for the condenser and as a foundation for the turbine elements. The entire power system therefore occupies a minimum amount of space, is of lesser weight than the systems heretofore employed and at the same time operates with extreme economy.

While I have shown my invention in but one form, it will be obvious to those skilled in the art that it is not so limited, but is susceptible of various changes and modifications, without departing from the spirit thereof, and I desire, therefore, that only such limitations shall be placed thereupon as are imposed by the prior art or as are specifically set forth in the appended claims.

What I claim is:—

1. In a marine installation, a surface condenser comprising a shell having a substantially horizontal upper portion for supporting a turbine installation, another portion of said shell being curved to substantially conform to the shape of the bottom and of the side of the ship, said horizontal and said curved portions of said shell being arranged to provide a relatively shallow condensing chamber, a longitudinally extending supporting member secured to said horizontal and to said curved portions of said shell for assisting in supporting the turbine installation, said supporting member having openings therein to permit the passage of gaseous media therethrough, heat transfer tubes within the shell and on each side of the sup-

porting member, and means for slidably supporting the shell on the structure of the ship at points directly beneath the longitudinally extending supporting member.

2. In a marine installation, a surface condenser comprising a shell having a substantially horizontal upper portion for supporting a turbine installation, another portion of said shell being curved to substantially conform to the shape of the bottom and of the side of the ship, said horizontal and said curved portions of said shell being arranged to provide a relatively shallow condensing chamber, a longitudinally extending supporting member secured to said horizontal and to said curved portions of said shell for assisting in supporting the turbine installation, said supporting member having openings therein to permit the passage of gaseous media therethrough, heat transfer tubes within the shell and on each side of the supporting member, means for securing the shell to the ship at the inboard and at the outboard sides of said shell, and means for slidably supporting the shell on the structure of the ship at points directly beneath the longitudinally extending supporting member.

3. In a marine installation, a condenser adapted to be connected to a turbine element and to support a plurality of turbine elements, said condenser having its lower portion conforming in shape substantially to the ship's structure, the inboard and outboard ends of the condenser being secured to the structure of the ship, a supporting member provided within the condenser between the inboard and outboard ends, and means for slidably supporting said member upon the structure of the ship.

4. In a condenser disposed in a ship's structure, the combination of a condenser shell structure having a top embodying a turbine supporting portion and embodying inlet means for the admission of turbine exhaust gases, a tube nest disposed within the shell structure, and a structural member supported upon the ship's structure and extending through the interior of the condenser shell between the ends of the tube nest and engaging the top of the shell structure, said structural member forming an internal bracing member for the shell structure and a means for supporting the turbine supporting portion of the shell structure directly from the ship's structure.

5. In a condenser disposed in a ship's structure, the combination of a condenser shell structure having a top embodying a turbine supporting portion and embodying inlet means for the admission of turbine exhaust gases, a tube nest disposed within the shell structure, and a structural member supported upon the ship's structure and extending upwardly through the interior of the shell structure between portions of the tube nest and

connecting with the turbine supporting portion of the condenser shell structure, said structural member forming an internal bracing member for the condenser shell structure and a means for supporting the turbine supporting portion of the shell structure directly from the ship's structure.

6. In a condenser in a ship's structure, the combination of a condenser shell structure having top and bottom wall portions, said bottom wall portion being disposed adjacent to the ship's structure and said top wall portion embodying a turbine supporting portion and also embodying inlet means for the admission of turbine exhaust gases, a tube nest disposed in the shell structure, a structural member disposed interiorly of the condenser shell structure intermediate of the ends of the tube nest and extending between the top and bottom wall portions, and means for supporting the condenser shell structure from the ship's structure and including a member supported upon the ship's structure and engaging the exterior of the condenser shell structure adjacent to the interiorly disposed structural member.

7. In a condenser in a ship's structure, the combination of a condenser shell structure having upper and lower wall portions, said lower wall portion being disposed adjacent to the ship's structure and said upper wall portion embodying a turbine supporting portion and embodying inlet means for the admission of turbine exhaust gases, a tube nest extending in a fore-and-aft direction within the condenser shell structure, and means for supporting the condenser from the ship's structure and including a structure extending vertically upward from the ship's structure and projecting through the condenser shell structure and engaging the turbine supporting portion of the upper wall portion, said vertically-extending structure being disposed in a fore-and-aft direction and having portions of the tube nest arranged on both the inboard and outboard sides thereof.

In testimony whereof, I have hereunto subscribed my name this 13th day of May, 1926.

HENRY F. SCHMIDT.
